D. L. REID

THERMOSTATIC CONTROL FOR WATER HEATERS

Filed Sept. 30, 1921

Inventor
David L. Reid

By Whitemore / Hubert Whitemore
+ Belknap Attorneys

UNITED STATES PATENT OFFICE.

DAVID L. REID, OF DETROIT, MICHIGAN.

THERMOSTATIC CONTROL FOR WATER HEATERS.

Application filed September 30, 1921. Serial No. 504,491.

To all whom it may concern:

Be it known that I, DAVID L. REID, a citizen of the United States of America, residing at Detroit, in the county of Wayne and 5 State of Michigan, have invented certain new and useful Improvements in Thermostatic Controls for Water Heaters, of which the following is a specification, reference being had therein to the accompanying 10 drawings.

This invention relates to thermostatic controls for water heaters.

It is the object of the invention to provide a simplified and positive thermostatic 15 control mechanism for automatically regulating the supply of gas to a water heater according to the resulting temperature.

In the drawings:—

Figure 1 is a diagrammatic view of an 20 improved apparatus, the thermostatic mechanism and the water tank being shown in section.

Figure 2 is a sectional detail of the adjusting means for the thermostat, the section being taken on line 2—2 of Figure 1.

Figure 3 is a section through a fitting employed in the mechanism.

In these views the reference character A designates a hot water tank and B a pipe for 30 delivering the heated water to said tank. Said pipe includes a coil B' beneath which is disposed a gas burner C. Gas is delivered to said burner by a pipe having the portions C' and C'', the former discharging into 35 a rectangular metallic casing D and the latter leading from said casing to said burner. Within said casing there is rigidly secured an annular fitting E, which has an exteriorly threaded reduced portion E' that extends 40 downwardly through the bottom of the casing that is connected to the pipe C''. For retaining the fitting E in firm engagement with the bottom of the casing D, I preferably provide a suitable lock nut E'' 45 that is threaded onto the reduced portion E' of the fitting and that engages the lower face of the casing. The top end of said fitting is conically beveled to form a seat engageable by a correspondingly shaped valve 50 F pivotally carried by the long arm G of a bell crank having a short downwardly projecting arm H. Said bell crank is pivotally mounted at the juncture of its arms as indicated at Q upon a lug J integrally projecting 55 from the inner end of a plug K mounted

in an end wall of said casing. Said plug has a screw threaded outer end portion which is tapped into the wall of the tank A and suitably sealed in said wall. Said plug rigidly carries a tube L of copper or a like metal which is readily responsive to variations of temperature, said tube projecting radially into said tank. Within said tube is centrally disposed a rod M of iron or a like metal which is relatively unresponsive to variations of temperature, the outer extremity of said rod being rigidly sealed within the free end of the tube L. Said rod at its other extremity is axially slidable within the plug K, projecting slightly beyond the inner end of said plug. N is a set screw adjustably carried by the short arm H of the crank and arranged to bear against the adjacent projecting end of the rod M in substantial alignment with said rod. To insure 70 said screw being held fixed in any desired position of adjustment, the arm H is split downwardly from said screw and the bifurcations thus formed are clamped upon the set screw N by a screw P engaging the 75 free ends of said bifurcations.

Discussing the operation of the mechanism as so far described, it is to be understood that the set screw N is adjusted with 80 relation to the rod M to normally maintain a predetermined temperature in the tank A through regulation of the gas supply to the burner C. Thus any increase of temperature in said tank above the predetermined point will result in an increased expansion 85 of the tube L which owing to the nature of said tube and the rod M will produce a slight shifting of said rod into said tank, this will permit a swinging of the bell crank, due to the weight of the valve F, shifting 90 said valve toward its seat and reducing the supply of gas to the burner C. Similarly a reduction of temperature in the tank A below the predetermined limit owing to the resulting relatively large contraction of the 95 tube L, shifts the rod M toward the bell crank rocking the latter to unseat the valve F and admit more gas to the burner. It is to be observed that the bell crank has the effect of considerably multiplying the movement of the valve resulting from any movement of the thermostatic rod M.

To permit the valve F to normally be fully seated, if desired, without extinguishing the flame of the burner there is provided 100

105

110

means for constantly maintaining a pilot flame at the burner independently of the thermostatic control. Thus the fitting E is integrally formed within the casing D with 5 a lug Q' in which is formed a restricted by-pass K' for admitting gas from said casing to said fitting below the valve seat of the latter. As a provision for regulating the flow of gas through said by-pass an 10 adjusting screw S is tapped into said lug and is adjustable to more or less obstruct the by-pass.

Among the desirable features of the described invention, may be mentioned the 15 absence of any springs to necessitate adjustment or replacement and an absence of any valve stems requiring packing, furthermore the construction is one that may be readily installed in connection with a gas 20 water heater or range boiler already in use. The construction serves to maintain a constant supply of hot water ready for use and any displacement of this supply will result immediately in the production of an 25 increased supply of gas to the burner until there is again produced a normal supply of

water in the tank at the predetermined temperature.

What I claim as my invention is:—

In a device of the class described, the 30 combination with a casing having a gas inlet and a gas outlet, and valve for regulating the passage of gas through said outlet, of control means for said valve including a plug mounted in a wall of said casing, a 35 lug projecting from the inner end of said plug, a bell crank lever pivotally mounted at the juncture of its arms upon said lug, the long arm of said lever being connected to said valve, a tube carried by said plug, 40 said tube being readily responsive to temperature variations, a rod within said tube, said rod being relatively un-responsive to temperature variations, the outer end of the rod being sealed within the free end of the tube, said rod at its other end being axially slidable within said plug, and a set 45 screw adjustably carried by the short arm of said lever and arranged to bear against the adjacent projecting end of said rod. 50

In testimony whereof I affix my signature.
DAVID L. REID.
